UNITED STATES PATENT OFFICE

ERNEST A. THOMFORDE, OF ENGLEWOOD, NEW JERSEY.

DESIGN FOR A CORN-HOLDER.

SPECIFICATION forming part of Design No. 28,023, dated December 14, 1897.

Application filed September 21, 1897. Serial No. 652,496. Term of patent 7 years.

To all whom it may concern:

Be it known that I, ERNEST A. THOMFORDE, a citizen of the United States, and a resident of Englewood, in the county of Bergen and State of New Jersey, have invented 5 a certain new and useful Design for a Corn-Holder, of which the following is a specification.

My design relates to the new and original 10 shape or configuration of the article and its respective portions.

The figure is an elevation of a corn-ear holder embodying my design.

The leading feature of this design comprises the holder, formed from a single wire 15 so bent in the middle that the substantially parallel parts form a handle, each member of which is so bent upon itself at the point of divergence as to form a guard or guide to prevent distortion, while the ends are returned 20 and bent into expanding helical coils of suitable size to grasp the ear of corn at the ends.

Referring now more particularly to the drawing, C is the middle of the wire, bent to form the handle d d. The wire is again bent 25 upon itself to form the engaging loops b b in the respective arms, and then turning in a suitable curve terminates in expanding helical coils f of proper size to grasp and hold the ends of the corn-ear without preventing 30 its revolution.

What I claim, and desire to secure by Letters Patent, is—

The design for a holder for corn-ears, substantially as shown and described.

Signed at Englewood, in the county of Bergen and State of New Jersey, this 24th day of March, A. D. 1897.

ERNEST A. THOMFORDE.
